UNITED STATES PATENT OFFICE

2,036,503

HEATING AND DRYING SYSTEM

Buford B. Russell, Chicago, Ill., assignor to Drying Systems Inc., Chicago, Ill., a corporation of Illinois

Application June 3, 1935, Serial No. 24,659

4 Claims. (Cl. 141—1)

This invention relates to heating and drying systems and more particularly to heating water employed in a parts washer and drying the washed parts.

5 Articles of manufacture are usually cleansed before being painted or otherwise finished and for other purposes. This is usually done by passing the articles, herein referred to as "parts", through a washer wherein cleansing is effected 10 by directing a multiplicity of streams of water on the parts. Hot water is usually employed and parts washers have been equipped with water heating means such as steam coils, gas burners, and the like, but all of such means are expensive 15 to install and operate and have other disadvantages. Where steam coils are employed it is often necessary to provide a boiler or to increase the capacity of the available boiler, either of which procedures is expensive and objectionable. 20 The washed parts are dried before the finishing operations are performed thereon and a variety of means have been employed for this purpose such as drying ovens which have been heated in different ways including the circulation of heated air therethrough and in such instances the air is usually heated to a temperature between 300° and 400° F.

The primary object of my invention is to employ heated air to heat wash water economically 30 and efficiently and to then utilize the air to dry parts or the like cleansed by the heated wash water.

Other objects are to employ a novel arrangement of simple and inexpensive equipment in 35 which air heated to a temperature sufficiently high to heat the water in a parts washer quickly may be passed directly from the washer to a dryer at a temperature proper for drying purposes; to withdraw heated air from an air heater 40 and force it through the washer and dryer and recirculate air flowing from the dryer through the air heater by the use of a single fan or blower; to afford efficient heat transfer in the washer between the air and water with minimum resist- 45 ance to the air flow; and to admit fresh air through necessary openings in the equipment and thereby avoid heat losses through these open- 50 ings and thereby temper the air and establish and maintain a predetermined temperature in the air supplied to the washer.

A selected embodiment of my invention is illus- 55 trated in the accompanying drawing wherein

Fig. 1 is a plan view, partly in elevation and partly in section, of a parts washer and dryer embodying my invention;

Fig. 2 is an end elevational view looking in at the right hand end of Fig. 1 and in which certain parts are broken away;

Fig. 3 is a fragmentary elevational view taken substantially on the line 3—3 on Fig. 1 and in which a part of the housing is broken away;

Fig. 4 is a transverse sectional detail view taken substantially on the line 4—4 on Fig. 1; and

Fig. 5 is a longitudinal sectional view through the air heater and taken substantially on the line 5—5 on Fig. 1.

In the embodiment of my invention illustrated in the accompanying drawing, 6 indicates the housing of a parts washer of suitable construction and which, as illustrated, has a monorail 15 track 7 at the top thereof along which suitable carriers may travel to convey the parts through the washer. A chain conveyor or the like could be used instead of the track and carriers. The parts pass into the washer through an opening 8 20 at one end of the housing and a dampered stack 9 is provided in the top wall of the washer adjacent this opening.

A metal tank 10 having good heat conductive properties is provided at the bottom of the washer adjacent the inlet end thereof. A bank of perforated pipes 11 is associated with this tank and the pump 12 forces saponified water from the tank through the perforations in a multiplicity of fine streams which strike the parts from all 30 angles and thoroughly cleanse the parts.

Another tank 13, similar to the tank 10, is provided with a bank of perforated pipes 14 and a pump 15 withdraws water from the tank and forces it through the pipes to rinse the parts and free them of any saponified water that may remain thereon. The water in the tank 13 is recirculated and some saponified water may collect therein. If this is true then the parts may be subjected to a final rinsing as is done in the illus- 35 trated device by being moved past a bank of perforated pipes 16 communicating with a tank 17, similar to the tanks 10 and 13. A pump 18 forces clear water through the perforations in the pipes 16 to thoroughly rinse the parts and thereby 40 facilitate drying thereof in the dryer. After passing the bank of pipes 16 the parts move out of the washer past a suitable spray confining means 19 with which a dampered stack 20 com- 45 municates.

The monorail 7 leads to the dryer 21 from the washer through an opening like the opening 8. A stack 22, having a trap 23 at the lower end thereof, leads to the stack 20 to create a draft 50 adjacent the inlet opening of the dryer and this 55

prevents ingress of fresh air into the dryer as well as egress of hot air from the dryer. The monorail 1 leads through the dryer 21 and the extension 23' thereof to the outlet opening 21'. 5 The parts move out of the dryer through the opening 21' and are then transported to suitable finishing equipment or the like to have finishing or other operations performed thereon.

The particular details of construction of the 10 parts thus far described forms no particular part of my invention except that the tank or tanks containing water to be heated, such as the tanks 10, 13 and 17, should be made of material having good heat conductive properties.

15 As best illustrated in Figs. 1 and 4, a jacket 24 is provided about the sides and bottoms of the tanks 10, 13 and 17. An inlet duct 25 leads into the lower part of the jacket 24 adjacent the inlet end of the washer. Air at relatively high temperature as, for example 700° to 800° F., is forced 20 through the inlet duct 25 into the jacket 24 from a suitable source, as will be explained.

While any form of air heater may be used I 25 have illustrated a heater particularly suited for the purpose. This heater, generally indicated by 26, includes a combustion chamber 27 having a fire opening 28 through which a flame, from an oil or gas burner 29 or the like, passes into the combustion chamber. A mixing chamber 30 is 30 provided in the heater above the combustion chamber 27. An air inlet opening 31 leads into the mixing chamber. A flue 32 is provided between the combustion and mixing chambers and air flowing through the mixing chamber to the 35 flue 33, leading from this chamber, withdraws the hot products of combustion from the combustion chamber through the flue 32 and these products are mixed with air in the mixing chamber and efficiently raise the temperature of the air. The 40 air thus heated flows out through the flue 33 and duct 34 to the intake of a fan or blower 35, and the heated air is discharged from the fan through the duct 36 into the inlet duct 25.

The fan 35 forces the heated air through the 45 ducts 36 and 25 and the jacket 24 and as the heated air flows through the jacket it gives up heat to the water in the tanks 10, 13 and 17. The cooperating walls of the tanks and the jacket preferably extend in parallel relation and 50 afford prolonged contact of the air with the tanks and this construction offers minimum resistance to the air flow and affords efficient heat transfer between the air and water. These advantages 55 and the fact that the tanks are substantially surrounded by heated air enables the water in the tanks to be heated efficiently and quickly to a relatively high temperature.

An outlet duct 37 leads from the jacket 24 near 60 the outlet end of the washer and this duct is extended along the bottom of the extension 23' and into the dryer 21. Heated air flowing from the washer through this duct flows into the dryer 21 and the extension 23' through the discharge 65 openings 38. This heated air effectively dries the parts passing through the dryer and the extension.

The temperature of air flowing from the jacket 24 into the duct 37 and out through the discharge 70 openings 38 retains sufficient heat to effect efficient drying. For example, if the temperature of the air admitted into the jacket 24 through the inlet duct 25 is between 700° and 800° F. and the velocity of this air as it flows through the 75 jacket 24 and the heat transfer is such that the

temperature of water in the tanks 10, 13 and 17 is raised close to the boiling point, the temperature of the air flowing from the duct 24 through the duct 37 will be between 300° and 400° F. which is a temperature closely corresponding to 5 the temperature to which air normally supplied to drying ovens is raised.

A collector 39 (Figs. 1 and 2) is provided in the upper part of the extension 23' at the discharge opening and a duct 40 leads from this 10 collector to the air inlet opening 31 in the air heater. The draft created by the fan 35 withdraws heated air from the upper part of the extension 23' and also draws fresh air in through the opening 21', and by reason of the ingress of 15 fresh air through the opening 21' the escape of heated air through this opening is avoided, this also being effected at the other parts inlet and outlet openings in the washer and dryer. The air which has flowed through the jacket 24 and 20 the dryer is therefore returned to the heater 26 and any heat remaining therein is recovered and this increases the efficiency of operation of the heater. In event sufficient return air is not supplied to the heater, a fresh air inlet 41 may be 25 provided in the duct 40. Furthermore, dampers, such as the dampers 42 and 43 provided in the duct 40 and the fresh air inlet 41, may be provided in the various ducts and these dampers may be adjusted to control the air flow to and 30 from the heater 26. The temperature of the air admitted into the jacket 24 through the inlet duct 25 may be regulated by a thermostat 25' (Fig. 1) which may be conveniently located in the duct 25 and this thermostat may be arranged to actuate suitable temperature controlling devices such as the valve 29' (Fig. 5) controlling flow to the burner 29. The thermostat 25' and the valve 29' may be electrically interconnected as by the conductors 27' and 28'. A 40 rise in the temperature of air flowing through the duct 25 affects the thermostat 25' which in turn causes the valve 29' to be actuated to reduce flow to the burner 29 whereby the temperature in the air heater 26 is reduced. A drop in 45 temperature in the duct 25 has the opposite effect, that is to say, the valve 29' is so actuated that flow to the burner is increased whereby the temperature in the air heater is raised.

An arrangement such as the foregoing may 50 be advantageously employed in those places where steam is not available for heating water. Further, by reason of the efficient manner in which air may be heated in a system such as the foregoing and the efficient heat transfer afforded in passing heated air over a metal container having good heat conductive properties and containing a liquid to be heated, efficient and economical heating of the liquid may be effected. Moreover, heat remaining in the air 60 after heating the water may be used to dry the parts by evaporating the surface water thereon. The efficiency of the system thus attained enables more economical operation than can be 65 realized by the use of steam coils or gas burners or other means for heating the water used in a parts washer. The system has the additional 70 advantage of simple and efficient control so that facile regulation of temperatures in various parts of the system may be expeditiously effected.

While I have illustrated and described the embodiment of my invention adapted for heating the wash water used in a parts washer and drying the washed parts it is to be understood 75 that the invention may be used for other pur-

poses and also that the invention is capable of variation and modification, and I therefore do not wish to be limited to the precise details set forth but desire to avail myself of such changes and alterations and other uses of the invention as fall within the spirit and scope of the following claims.

I claim:

1. In a washing and drying system, a parts washer having a water tank therein, a jacket disposed about said tank, a dryer to which parts washed in the washer are passed to be dried, a duct leading from said jacket to said dryer, air heating means, and means for forcing heated air from the air heating means through said jacket and said duct into the dryer, said air heating means sufficiently heating the air to heat water in said tank substantially to the boiling point and supply air to said dryer hot enough to effect drying of the parts therein.
2. In a washing and drying system, a parts washer having a water tank therein, a jacket disposed about said tank, a dryer to which parts washed in the washer are passed to be dried, a duct leading from said jacket to said dryer, air heating means, a fan for withdrawing heated air from said air heating means and for forcing the heated air through said jacket and said duct into the dryer, said air heating means sufficiently heating the air to heat water in said tank substantially to the boiling point and supply air to said dryer hot enough to effect drying of the parts therein, and a return duct leading from said dryer to said air heating means and through which air is drawn from said dryer to said air heating means by said fan to recover heat remaining in the air after it has flowed through the dryer.
3. In a washing and drying system, a parts washer having a water tank therein, a jacket

disposed about said tank, a dryer to which parts washed in the washer are passed to be dried, a duct leading from said jacket to said dryer, air heating means, means forcing heated air from the air heating means through said jacket and said duct into the dryer to heat water in said tank and supply heat to said dryer, and means for regulating the temperature of air flowing from said air heating means and operating to maintain the temperature of the air sufficiently high to maintain the temperature of the water in the tank substantially at the boiling point whereby variations in the temperature of the air flowing from the air heating means may vary the temperature in said dryer without substantially affecting the temperature of heated water in said tank.

4. In a washing and drying system including a washer and a dryer, a conveyor for conveying parts to be cleansed and dried successively through the washer and dryer, said washer including a water tank and means for directing water from said tank onto the parts to effect cleansing thereof, air heating means, means for directing heated air from the air heating means past said water tank to heat water therein substantially to the boiling point and then into the dryer to supply heat to the dryer wherein the parts are dried, and means for regulating the temperature of air flowing from said air heating means and operating to maintain the temperature of the air sufficiently high to maintain the temperature of the water in the tank substantially at the boiling point whereby variations in the temperature of air flowing from the air heating means may vary the temperature of the air flowing into the dryer from the water tank without substantially affecting the temperature of the heated water in said tank.

BUFORD B. RUSSELL. 40
